UNITED STATES PATENT OFFICE

JAMES FRANKLIN HENNESSY, OF WINONA, MINNESOTA, ASSIGNOR TO HIMSELF, HENRY M. KINNEY, AND THE WINONA WAGON COMPANY, ALL OF SAME PLACE.

SLEIGH-KNEE.

SPECIFICATION forming part of Letters Patent No. 379,394, dated March 13, 1888.

Application filed August 2, 1887. Serial No. 245,928. (No model.)

To all whom it may concern:

Be it known that I, JAMES FRANKLIN HENNESSY, of Winona, in the county of Winona, and State of Minnesota, have invented a new 5 and Improved Sleigh-Knee, of which the following is a full, clear, and exact description.

My invention relates to knees for connecting runners to the beams of sleighs, and has for its object to provide a simple, inexpensive, 10 and efficient device of this character which will allow limited vertical and lateral play of the runner that it may accommodate itself to irregularities of the road on which the sleigh travels, and without overstraining the runner, 15 the beam, or the reach which connects the front and rear runners of a bob-sleigh.

The invention consists in certain novel features of construction and combinations of parts of the sleigh-knee and its connections 20 to the runner and beam, all as hereinafter described and claimed.

Reference is to be had to the accompanying drawings, forming a part of this specification, in which similar letters of reference indicate 25 corresponding parts in all the figures.

Figure 1 is a side elevation of my improved sleigh-knee as applied to use. Fig. 2 is a transverse vertical sectional elevation thereof. Fig. 3 is an under side view of the cap of the knee, 30 and Fig. 4 is a perspective view of one of the bolts used to connect the knee-cap to the knee and sleigh-beam.

The sleigh-knee proper, A, is provided with the usual opposite side flanges, *a a*, which lap 35 onto the sides of the runner B, to which the knee is bolted. At its head or top part the knee is provided with a couple of half-rounded or convex lugs, C C, between which and transversely of the knee is formed a recess, *c*, having a convexus bottom and adapted to receive 40 a lug, *d*, formed at the center of a cap-plate, D, which at opposite ends of said lug has recesses *d' d'*, receiving the lugs C C on the knee. The cap-lug *d* is tapered at the sides each way 45 from its transverse center, as clearly shown in Fig. 3, or the lug *d* may be rounded at each side, and the recess *c* of the knee is about straight at the sides. The cap-recesses *d'* are concaved in the arc of a larger circle than the

convexity of the knee-lugs C C is struck upon, 50 and these recesses will preferably be slightly flared at the sides from the lug *d*, and whereby, when the cap is held to the knee and to the sleigh-beam E by the pair of pivot-bolts F F, the sleigh-runner B and the knee A, rigidly 55 attached to the runner, may together have lateral movement in the cap B and on the lug *d* as a center of motion, to allow a limited but ample lateral play either way of the front and rear ends of the runner to allow it to freely 60 accommodate itself to the road on which the sleigh may travel.

The pivot-bolts F have a right-angular general form, their lower horizontal parts, *f*, passing rather loosely through the knee-lugs C C 65 and into the cap-lug *d* from opposite sides of the knee, while their outer vertically-ranging parts, *f'*, pass through slots *g g*, formed in lugs G G, provided on the opposite ends of the cap D. The angular corner of each of the 70 bolts F is formed with a flat vertical shoulder, *f²*, which abuts the outer end of the adjacent knee-lug C, and is provided, also, with a horizontal shoulder, *f³*, which is drawn up snugly to the lug G by the nut *f⁴*, which is screwed 75 onto the upper end of the bolt and preferably upon a washer interposed between it and the beam E, which ranges transversely of the sleigh, and to which the sleigh-body will be held in any approved way, and which may be 80 connected by a reach with another beam provided with runners to form a bob-sleigh in a manner well understood.

The opposing faces of the knee A and the cap D at the front and rear of their lugs C C d 85 are so formed relatively with each other that, while the cap has a substantial bearing on and in the top of the knee, the knee will have a limited front and rear vertical play or rocking motion under the cap to allow the front and 90 rear ends of the runner B to rock or pitch up and down as much, and only so much, as will be necessary to allow the runner to accommodate itself to uneven places along the road without overstraining the parts of the sleigh, and especially the reach, by which the front and rear bobs of the sleigh will be connected. I prefer 95 to slope or slightly bevel off the opposite up-

per faces or shoulders, $c^2 c^2$, of the knee-top at each side of the lugs C C and to leave the opposing side faces, $d^2 d^2$, of the cap D about level, and so that the cap-faces form stops to the knee-faces c^2 to limit the rocking of the runner; but it is obvious that the same fore-and aft limited vertical play or rocking of the runner would be permitted were the faces c^2 flat or level and the opposing faces, d^2 , of the cap beveled, or if both faces $c^2 d^2$ were either beveled or flat, if sufficient space be allowed between them while the cap bears on the knee-lugs C C.

The cap D is provided at opposite sides with pendent lips or flanges H H, which overlap or overhang the adjacent outer edges of the top faces, $c^2 c^2$, of the sleigh-knee, and effectively prevent entrance of snow, ice, or other substance between the cap D and runner, which, if allowed, would seriously interfere with or prevent the limited and desirable fore-and-aft vertical rocking of the runner above described.

It is manifest that a sleigh-knee and cap constructed as above described, and allowing limited lateral play and also vertical fore-and-aft rocking or pitch of the runner, would operate with like good results were the lugs C C d pivoted together by one bolt and the cap D held to the sleigh-beam by two other bolts, one at each end of the cap; hence the special form of the bolts F is a distinctly novel and desirable feature of my invention, as by their use but two bolts are required to hold each knee and cap to the runner and beam, and the parts of the sleigh may readily be dismembered for making repairs by simply unscrewing the two nuts f^4 , which are conveniently accessible at the top of the sleigh-beam. Furthermore, the sleigh may be shipped in knockdown condition, and may be easily set up by first securing the knee A to the runner, then laying the cap D on the knee, then slipping the parts f of the bolts F into the lugs C C d of the knee and cap, while the parts f' of the bolts enter the end slots, g , of the cap, and then setting the beam E on the

parts f' of the bolts, and finally screwing up the nuts f^4 of the bolts and above the beam, as will readily be understood.

While the above-described sleigh-knee renders the sleigh very easy and pliable or yielding on the road, the knee is at the same time very substantial, and a sleigh whose runners and beams are coupled by the knees is capable of hard and long-continued service.

Having thus described my invention, what I claim as new, and desire to secure by Letters Patent, is—

1. The combination, in a sleigh-knee, of a knee proper, A, formed with lugs C C and a recess, c , between them, a cap, D, provided with recesses $d' d'$, adapted to receive the knee-lugs C C loosely, and formed also with a lug, d , adapted to the knee-recess c , and a pair of right-angular bolts entered into the lugs C C d from opposite sides of the knee and passing also through the cap and beam and receiving nuts above the beam, substantially as described, for the purposes set forth.

2. The combination, in a sleigh-knee, of a knee proper, A, formed with lugs C C and a recess, c , between them, a cap, D, provided with recesses $d' d'$, receiving the lugs C C loosely, and formed also with slots g and with a lug, d , adapted to the knee-recess c , and a pair of right-angular bolts, F F, having shoulders $f^2 f^3$ at their corners and passed through the lugs C C into the lug d from opposite sides of the knee, and passed also through the cap-slots g and the beam and receiving nuts f^4 above the beam, substantially as described, for the purposes set forth.

3. The sleigh-knee bolts F, formed with a part, f , and an angularly-disposed threaded part, f' , receiving a nut, f^4 , and connected to the part f by a corner-piece provided with shoulders $f^2 f^3$, substantially as described, for the purposes set forth.

JAMES FRANKLIN HENNESSY.
